UNITED STATES PATENT OFFICE.

JACOB D. HOOVER, OF WINCHESTER, VIRGINIA, ASSIGNOR OF ONE-FOURTH
TO JOSEPH T. FISHER, OF WINCHESTER, VIRGINIA.

CAR-COUPING.

SPECIFICATION forming part of Letters Patent No. 695,053, dated March 11, 1902.

Application filed January 10, 1902. Serial No. 89,149. (No model.)

To all whom it may concern:

Be it known that I, JACOB D. HOOVER, a citizen of the United States, residing at Winchester, in the county of Frederick and State 5 of Virginia, have invented new and useful Improvements in Car-Couplings, of which the following is a specification.

This invention relates to certain new and useful improvements in car-couplings, and 10 has reference more particularly to means for uncoupling cars, such uncoupling being effected by lifting a locking-block, which can be effected either by manual operation thereof or by the engineer on the locomotive, when 15 the attendant sets such feature of the mechanism so as to be under the control of the engineer. By the construction which will be hereinafter set forth the engineer can uncouple a car or cars from the train and may have 20 any particular coupler under his control.

The present invention is applicable to the couplings either of freight or passenger cars, wherein is combined a horizontally-pivoted and vertically-vibrating locking-block which 25 engages the tailpiece of the knuckle, said knuckle raising the locking-block when swung in one direction, said locking-block holding the knuckle against movement in an opposite direction when it falls or is lowered 30 by gravity, as will be hereinafter set forth.

In the accompanying drawings, Figure 1 is a plan view, partly in section, of a car-coupling constructed in accord with my invention. Fig. 2 is a side elevation, partially in 35 section. Fig. 3 is a vertical section taken through the coupler-head, and Fig. 4 is a detail perspective view of the vibrating locking-block.

In the drawings, A refers to the coupler-head, to which a knuckle B is pivoted, being 40 held in swinging engagement therewith by a vertical pin a. The knuckle is provided with the usual tailpiece b, the rear upper end of said tailpiece where it engages with the locking-block being rounded or beveled for engagement with the locking-block to lift the same when swung toward one of the walls of the coupler-head. The coupler-head has an aperture or recess through one of its vertical 45 side walls, which is covered externally by a socketed cap-piece a', which carries or holds a spring c, which spring bears upon the knuc-

kle and swings the same beyond the locking-block when not restrained thereby. The locking bar or latch D is loosely mounted on a 55 pin or shaft d, which is carried or journaled horizontally in the rear portion of the coupler-head, and this shaft is provided with a spline or feather d', which is adapted to engage with the end walls of a recess or enlargement d² 60 of an aperture d³ through the locking-block D. The feather or spline is positioned in such relation to the recess that when the locking-block is lowered the spline will be against or adjacent to the upper wall of the recess, and 65 when so placed arms D' D² on the ends of the shaft will be forwardly inclined, so as to overbalance and hold the shaft in such position.

To raise the locking-block so that the knuckle will be forced or swung away from 70 the side wall of the coupling-head by a manual operation of the locking-block, the arm D' may be moved rearwardly by rocking the crank-arm E in its bearings, and the inner member of said crank-arm is connected to the 75 arm D' by a flexible connection or chain e. When it is desired to raise the locking-block from the top of the car, a rod G is depressed, said rod being adjacent to the brake-rod F, and when depressed the rod G engages its 80 supporting-spring g, which also contacts with a recess in a spool g', which is mounted on the brake-rod, said brake-rod having a stud or pin which is adapted to engage with serrations or notches in the lower head of the spool. The 85 spool has attached thereto a chain or flexible connection which extends therefrom to the arm D², so that by turning the brake-rod the chain will be wound on the spool and rock the shaft which carries the locking-block. As 90 soon as pressure is taken off the bar G the spring will lift the spool, so that it will turn on the brake-rod and permit the arms and shaft d to resume by gravity their usual position.

In freight-cars the brake-rod and rod G will 95 extend above the top of the car, and on passenger-cars these rods terminate a short distance above the platform. The chains or flexible connections have sufficient slack to allow 100 for a movement of the coupler-head without tightening such connection, and in the present instance the arms are located in close proximity to the coupler-head.

The locking-block D is essentially a gravity-lock—that is, it will fall into position automatically to lock the knuckle by engagement with the tailpiece thereof when not restrained by the feather or spline on the rock-shaft, and said rock-shaft is normally held by being over-weighted by the arms in such position that the spline will be on a horizontal line or project forwardly, so as to allow the locking-bar 10 and the shaft to assume their normal positions solely by gravity.

The locking block or catch D is provided with a rounded or beveled end, against which the rounded or beveled end of the knuckle 15 will engage to lift the latch when the tailpiece contacts therewith in its movement toward the side of the coupling-head having the spring, and when the tailpiece of the knuckle has passed the locking-block the same will 20 fall, the straight edge thereof engaging the straight edge or face of the tailpiece.

The coupling-head has an opening f through its under side, which is positioned slightly in advance of the shaft b, and in said opening 25 is secured a pipe or tube I, which extends upward and forms a rest or bearing for the locking-block, and the depending portion of the pipe carries a cock or cut-off, below which the pipe is connected to a pipe which extends 30 therefrom to the pipe of the coupler-head on the other end of the car, suitable flexible connections being provided. The pipes I' are provided with short sections for coupling the pipes I' together, such couplings being of the 35 type used upon air-brakes, and these couplings extend to the tender, and from thence the pipes lead to the cab of the locomotive, so as to be under the control of the engineer, who can let compressed air or steam into the 40 pipes I' and when the cocks k are properly turned therefrom through the upper end of the pipes I against the locking-block to lift the same and release the coupler when desired.

45 The locking-block is constructed so as to have on its under side a flat face or portion, in which is formed a recess d⁴ of such diameter as to admit therein the upper end of the pipe I, and said recess has a circular depending portion which lies within the bore of the 50 pipe, providing a supplemental circular recess which receives the upper end walls of the pipe I. The pipe provides a support which limits the downward movement of the locking-block, and the recess with which the spline or feather on the shaft d engages may limit the upward movement of the locking-block.

From the foregoing it will be seen that the 60 brakeman or attendant has only to set the cock k, and after it has been set the engineer can uncouple such car from the train and will have complete control of the locking-block of such coupler. The spring behind the tailpiece of the knuckle throws the same 65 beyond the locking-block when it has been raised.

The pipes I' may be used to convey either

compressed air or steam, and by the construction shown I avoid the use of pistons, cylinders, and springs, the compressed air or 70 steam acting directly upon the locking-block and throwing the same upward when it is desired to release the knuckle. The frame supporting the coupler may be constructed to provide converging side members and cross-bars, and such frame will be of metal and supported or attached to the car-frame in any suitable manner.

I claim—

1. In a car-coupling, the combination with 80 a swinging knuckle, a locking-block, of a pipe which extends through the coupling-head and is engaged by the locking-block when it is lowered, means attached to the outer end of the pipe for supplying compressed air or fluid 85 under pressure to said pipe and against the locking-block to move the same out of the path of the knuckle.

2. In a car-coupling, the combination with 90 a knuckle, its tailpiece, and a locking-block 95 which is mounted to vibrate on a horizontal pin and is provided forward of said pin with a recess, of a pipe which projects through the coupler-head and forms when seated in the recess a support which limits the downward 95 movement of the locking-block, a cock in said pipe and connections between the lower end of the pipe and a fluid-supply under pressure, substantially as set forth.

3. In a car-coupling, the combination with 100 a knuckle, its tailpiece, and a horizontally-pivoted locking-block whose center of gravity is forward of its pivot, of a pipe or tube against which the locking-block bears to maintain it in a horizontal position, a pipe 105 for conveying fluid under pressure to the first-mentioned pipe, and a cock or cut-off between such pipes.

4. In a car-coupling, the combination with 110 a knuckle, its tailpiece, a spring which engages the coupling-head and tailpiece, a horizontally-pivoted locking-block for engagement with the tailpiece, of means for manually raising the locking-block out of engagement with the tailpiece, and means for forcing a blast of air under pressure against the locking-block to effect a movement thereof without direct connection between the locking-block and such lifting means, substantially as set forth.

5. In combination with a car-coupling, the coupling-head having a gravity-locking block, a pipe which extends through the coupler-head and terminates beneath the locking-block, a recess in the locking-block which is 125 adapted to overlie the end of the pipe, substantially as shown and for the purpose set forth.

In testimony whereof I have hereunto set my hand in presence of two subscribing witnesses.

JACOB D. HOOVER.
